United States Patent Office.

J. W. UPHAM, OF WORCESTER, MASSACHUSETTS.

Letters Patent No. 91,691, dated June 22, 1869.

IMPROVEMENT IN TURBINE WATER-WHEELS.

The Schedule referred to in these Letters Patent and making part of the same.

To all whom it may concern:

Be it known that I, J. W. UPHAM, of the city and county of Worcester, and Commonwealth of Massachusetts, have invented certain new and useful Improvements in Water-Wheels, of which the following is a full, clear, and exact description, reference being had to the accompanying drawings, forming a part of this specification, in which—

Figure 1 represents a side view of so much of a water-wheel as is necessary to illustrate my present improvements, and

Figure 2 represents top or plan view of the parts shown in fig. 1, with a portion of the top of the casing of the wheel broken away, several of the buckets and water-guides being shown in section, as will be hereafter explained.

To enable those skilled in the art to which my invention belongs, to make and use the same, I will describe it more in detail.

The nature of my invention consists in the combination of adjustable inner water-guides with stationary outer water-guides, as hereafter explained.

In the drawings—

A is the upper casing, and

B, the lower casing of the wheel C, which is secured to the shaft in the usual manner.

Between the upper and lower rims of the wheel are fitted the buckets E.

Water is admitted to the buckets E, between the stationary outer guide-pieces F, and the inner adjustable guide-pieces G, the latter being fitted to turn on journals a, which fit in holes in the upper and lower rims of the casing of the wheel.

The centre of the adjustable guides G, projects outward, as shown in fig. 2, which not only gives strength to the guides, but also enables the journals a to be arranged out as far as possible.

The upper ends of the journals a are made so as to project through the upper casing, to receive the slotted arms H, which straddle the pins b in the movable ring I, arranged to turn on the rim of the casing-part A.

By reference to the drawings, fig. 2, it will be seen that the water-spaces c, between the guide-pieces F

G, can be narrowed at pleasure, by simply turning the ring I, to which all the journals a, of the adjustable water-guides G, are attached.

Ring I may be turned in any convenient manner. It may be connected by arms to a central tube on shaft D, or it may be provided with a rack, to be operated by a gear or worm-screw, on the end of a shaft.

The great advantages of my present improvements, consist in the facility with which the water-ways or channels c, can be contracted or enlarged, to admit less or more water to the buckets E, as occasion may require, and that, too, without changing the direction of the water which impinges upon the outer part of the buckets.

The inner faces of the water-guide pieces F, can be made in the form calculated to convey the water to the buckets, to produce the best effect, and is not changed when the water-spaces are contracted, the contraction being from the inside.

The water-guides G being nearly balanced by the water, can be easily operated, to adjust them to admit more or less water, or even closed. (See red and blue lines in fig. 2, as an illustration of the manner in which the water-guides G can be adjusted.)

Ring I is provided with a notch, e, to fit the stop f, whereby its motion in either direction is so limited as not to injure the water-guides G, by being moved too far in either direction.

Only two slotted arms are shown in the drawings, combined with journals a, of the water-guide pieces G, as they are sufficient to illustrate the manner in which all the latter are to be constructed and arranged.

Having described my improvements in water-wheels, What I claim therein as new and of my invention, and desire to secure by Letters Patent, is—

The adjustable inner water-guide pieces G, in combination with the stationary water-guide pieces F, substantially as and for the purposes set forth.

J. W. UPHAM.
